CLAIM

U.S. PATENT DOCUMENTS

The ornamental design for a cartridge for a hand-held electronic toy, as shown and described.

DESCRIPTION

FIG. 1 is a perspective view of a cartridge for a hand-held electronic toy showing my new design;

FIG. 2 is a front view of the cartridge illustrated in FIG. 1; FIG. 3 is a top view of the cartridge illustrated in FIG. 1; FIG. 4 is a left side view of the cartridge illustrated in FIG. 1; and,

FIG. 5 is a right side view of the cartridge illustrated in FIG. 1.

The portion of the article depicted in broken lines is for illustrative purposes only and forms no part of the claimed design.
